TYPEWRITING MACHINE

Frederick A. Hart, New Britain, Conn., assignor to
Remington Typewriter Company, Ilion, N. Y., a
corporation of New York

Application April 15, 1930, Serial No. 444,450

57 Claims. (Cl. 197—128)

My invention relates to typewriting and like machines and more particularly to billing mechanism therefor.

One of the main objects of my invention, generally stated, is to provide comparatively simple and inexpensive, yet highly efficient means that enable entries to be simultaneously made on a comparatively narrow bill sheet and on a comparatively wide ledger sheet, the entries appearing in a vertical arrangement on the bill sheet and in a horizontal arrangement on the ledger sheet.

A further object of my invention is to provide means of the character specified that are in the nature of an attachment that may be readily applied to or disconnected from a standard typewriting, or combined typewriting and computing machine, without modifying, or materially modifying, the existing structural features thereof.

To the above and other ends which will hereinafter appear my invention consists in the features of construction, arrangements of parts and combinations of devices set forth in the following description and particularly pointed out in the appended claims.

In the accompanying drawings, wherein like reference characters, designate corresponding parts in the different views:—

Fig. 1 is a fragmentary, side view, with parts in section, of the upper portion of a typewriting machine equipped with the devices of my invention.

Fig. 2 is a vertical, transverse sectional view of the same taken on the line 2—2 of Fig. 1 and looking in the direction of the arrows at said line.

Fig. 3 is a vertical, fore and aft sectional view of the auxiliary carriage and some of the associated parts; the section being taken on the line 3—3 of Fig. 2 and looking in the direction of the arrows at said line.

Fig. 4 is a fore and aft vertical sectional view disclosing some of the parts disclosed in Fig. 1; the section being taken on the line 4—4 of Fig. 2 and looking in the direction of the arrows at said line.

Fig. 5 is a fragmentary, detail, sectional view of part of the means for connecting the supporting frame for the auxiliary carriage with the platen carriage; the section being taken on the line 5—5 of Fig. 4 and looking in the direction of the arrows at said line.

Figs. 6, 7 and 8 are detail rear views of the locking bar, showing in conjunction therewith a

so-called shielding bar that may be set or adjusted to different positions to determine which of the notches in the locking bar may be left open for use.

Fig. 9 is a detail perspective view of one of the side guides and work sheet supporting devices.

Fig. 10 is a detail, fragmentary, perspective view of the means by which a pair of the bearing rollers for the auxiliary carriage are mounted.

Fig. 11 is a fragmentary face view of one form of ledger sheet intended for use in the machine, and a showing of which aids in arriving at an understanding of the use and operation of the machine and the entry of the items in horizontal lines thereon.

Fig. 12 is a face view of a bill sheet written in conjunction with said ledger sheet and indicating how the items are disposed vertically thereon, whereas the same items are entered horizontally on the ledger sheet.

Fig. 13 is a face view of an indicating strip cut from a ledger sheet and which is mounted on the support for the auxiliary carriage to aid in positioning or adjusting said carriage on the platen carriage.

The mechanism of the present invention is intended to attain some of the same general ends as the machine disclosed in the patent to Farnham, Smith and Phelps No. 1,071,612, dated Aug. 26, 1913. The machine disclosed in said patent involves a complicated, very expensive structure, specially constructed in its entirety.

One of the main objects of the present invention is to produce a machine which in the main will meet the requirements of said patented machine and that nevertheless, may be sold at a fraction of the price for which said patented machines were sold, and with as great, or even a greater profit to the manufacturer.

The machine to which I have shown the devices of my invention applied in the present instance is a No. 23 Remington front feed book-keeping machine to which said devices may be readily applied in the nature of attachments, without modifying, or materially modifying the existing structural features thereof. It should be understood, however, that the invention is not restricted to embodiment in such machines, but may be employed in typewriting, accounting and like machines generally, wherever found available.

The above mentioned Remington machine is disclosed in part in the application of Hart and Walsoe, Serial No. 221,543, filed Sept. 23, 1927,

and only so much thereof is disclosed herein as is necessary to illustrate my invention in its embodiment therein.

While the machine of the present invention is capable of a wide range of uses, it will be sufficient if I first give a general and brief description of one of such uses and describe briefly how it is carried out; thereafter describing in detail the construction and operation of the machine in connection with the particular use set forth, by way of example.

The example taken involves the use of a ledger sheet L, shown in Fig. 11, and a bill or primary work sheet B such as is illustrated in Fig. 12. It will be observed that the ledger sheet is ruled with a series of vertical columns a, b, c, d, e, f, g, h, i, j, each under an appropriate caption, such as "Line numbers", "State", "City", "Total tax", "Paid in full", "Date", "Refunds", "Remarks". A cross line entry in the different columns, or such of them as may be required, and on a single numbered cross line is made for each bill. Instead of having a bill sheet of a width equal to the ledger sheet, on which these various items are entered I propose to employ a comparatively narrow bill sheet B and enter the same items or some of them thereon in a vertically disposed arrangement as shown in Fig. 12, and to make each of such entries simultaneously on both the bill and ledger sheets. By my invention I provide simple and effective means by which this may be accomplished. Such means include a bill or primary work sheet carrying auxiliary carriage mounted on the platen carriage for step-by-step letter spacing movement therewith and for independent shifting movement along the same to bring the bill sheet into register with another part or vertical column on the ledger sheet for the next entry, and so on with successive entries. Each entry on the bill sheet is duplicated through an interposed carbon sheet on the ledger sheet. Work sheet feeding means are employed to advance the bill sheet independently of the platen and ledger sheet after each item entered, so that the different items of a bill will appear in a horizontal line across the ledger sheet but will be vertically disposed on the bill sheet.

With the foregoing preliminary description I will now describe in detail the present embodiment of my invention in the hereinbefore mentioned Remington machine.

In said machine a platen carriage 1 carries a cylindrical platen 2 and is mounted on bearing rollers 3 to travel over the top plate 4 of the machine from side-to-side thereof, the bearing rollers being supported in the grooved ways in fixed guide rails 5 and 6 secured to the top plate of the machine. The carriage is spring impelled in the direction of its feed under control of the usual carriage escapement mechanism (not shown) and the platen is actuated in the usual manner to effect a line spacing operation thereof.

Two curved paper deflectors 7 and 8 are arranged beneath the platen, being maintained spaced apart to provide a channel 9 between them. A work sheet, say, a comparatively wide ledger sheet L is introduced into the machine from the rear of the platen and into the space between the platen and the deflector 7, being carried around in front of the platen and beneath the usual feed rollers 10 located above the printing line, if said feed rollers are to be used, as will hereinafter more clearly appear. Whether or not said feed rollers 10 are to be used

will depend somewhat on the character of the ledger sheet employed, and whether there are sufficient side margins on the ledger sheet, not to be filled in, to enable the feed rollers 10 to coact with said margins of the sheet. Of course if the feed rollers 10 are not to be used they may be moved forward to and held in the ineffective position, shown in Fig. 4, by merely shifting the usual finger piece 10a forward from the Fig. 1 position. If the rollers 10 are to be used, then in any set-up they will be adjusted laterally to coact with the side margins only of the relatively wide sheet L, so that in no event will the feed rollers 10 interfere with a lateral shifting of the bill sheet B to overlap any desired portion of the ledger sheet L, as will hereinafter more clearly appear.

Outside of ledger sheet, and substantially co-extensive in size therewith, is a carbon sheet C by which a manifold copy of the items written on the bill sheet may be produced on the ledger sheet.

Both the ledger and carbon sheets, in the present instance, pass beneath paper feed rollers which bear on the top of the platen. In said prior Remington machines said feed rollers were carried by a bail. In the present construction this bail is omitted and feed rollers 11, preferably two in number, are mounted in the usual manner for adjustment along a rod 12 that constitutes a cross bar connecting two side plates 13 of a supporting frame, which will be hereinafter more fully described. The weight of this supporting frame and the parts carried thereby effectively holds the feed rollers 11 against the platen or the sheets C and L thereon.

The outermost or primary bill or work sheet B is introduced rearward from in front of the platen with its lower end foremost into the open mouth of the unobstructed channel 9 provided between the two paper deflectors 7 and 8. In thus introducing the lower end of the bill sheet into the channel 9 the usual front deflector 14 may be brought to the Fig. 4 position and aid in the introduction of the sheet, the usual printing line indicator 15 having at this time been moved to the ineffective position.

As indicated in Fig. 2 there are two side edge guides or gages 16 on an auxiliary carriage, said gages being spaced apart to correspond to the width of the bill sheet and between which the bill sheet is received and by which it is guided. Each of these side guides is formed as a part of a supporting plate 17 on which a bill sheet is adapted to rest and be supported. As shown in Fig. 9 each member 16-17 has rearwardly directed perforated ears 17a 17b, each ear 17a also having fixed thereto an inwardly extending hub 20 tapped to receive a set screw 21. The auxiliary carriage by which the parts 16-17 are carried comprises end plates 18 and 19 rigidly united by suitable cross bars or rods 22 and 23. The cross rod 23 passes through the perforations in the ears 17b, whereas the cross rod 22 passes through the perforations and hubs 20 of the ears 17a. In this manner the members 16-17 are supported on and may be adjusted along the cross rods 22 and 23 and may be spaced apart to coact with bill sheets B of various widths. A threading of the screws 21 causes them to engage the rod 22 and hold the members 16-17 in their adjusted positions.

The auxiliary carriage is supported on a cross bar 24 that in normal position is arranged above the platen and parallel with the axis thereof.

Said cross bar extends throughout the length of the carriage and is fixed at its ends by screws 25 to the end plates 13 of the supporting frame and may be regarded as a part thereof. In the 5 present instance the auxiliary carriage is supported to travel along the cross bar 24 by four grooved rollers 26 which coact with the opposite V-shaped edges of the bar. As shown in Fig. 10 a pair of said rollers are supported on two 10 inwardly extending ears 27 formed, in the present instance, integral with each end plate 18 of the auxiliary carriage. Each ear 27 has a spindle 28 detachably secured thereto and projecting forwardly therefrom. The forward end of each 15 spindle is provided with bearings for anti-friction balls 29 that provide a ball bearing for the associated bearing roller 26. This has proved to be an efficacious manner of connecting the bearing rollers to the auxiliary carriage since 20 the comparatively long line of supporting connections between each roller and the associated side plates of the auxiliary carriage affords a slight resiliency that enables said carriage to move freely along the cross bar 24 notwithstanding 25 lack of absolute trueness of the bar, which ordinarily might cause the auxiliary carriage to stick or bind thereon. The auxiliary carriage is, nevertheless, guided with sufficient accuracy, and with a freedom that enables it to be quickly positioned by hand to any desired selected point along 30 the platen carriage.

Means are provided on the auxiliary carriage for holding a bill sheet and advancing it in a line-feed direction independently of the platen 35 and the ledger sheet thereon. Such means, as they are embodied in the machine in the present instance, will now be described.

Paper feed rollers 30 are fixedly, though adjustably, secured to a driving shaft 31 by screws 40 32. A loosening of each screw 32 enables the associated feed roller 30 to be adjusted along the shaft 31 and secured in its adjusted position on said shaft, thus affording such an adjustment of the feed rollers as may be required for bill 45 sheets of different widths.

The driving shaft 31 is supported in bearing openings in the lower ends of two pivoted arms or plates 33 and 34. The arm 33 is pivoted at its upper end on the reduced portion 35 of a 50 shouldered screw bolt 36 secured to the end plate 18 of the auxiliary carriage, as shown in Fig. 2. An inwardly projecting pin 37 on the arm 33 forms an abutment for one end 38 (see Fig. 4) of a spring that is coiled around the enlarged portion 55 of the screw bolt 36 and bears at its other end 39 against a pin 40 projecting in from the end plate 18. The force of this spring is exerted to move the shaft 31 rearwardly and maintain the feed rollers 30 in effective position against 60 the bill sheet and against a suitable support therefor. In the present instance such support is represented by a series of paper feed rollers 41 mounted on and adjustable along a rock shaft 42 mounted in the end plates 18 and 19 of the auxiliary carriage. The power of the spring 38-39 is exerted to maintain the feed rollers 30 against the rollers 41, with a bill sheet interposed between them.

A corresponding spring coacts in a like manner with the arm or plate 34 to attain the same ends, so that both ends of the shaft 31 will be spring-pressed rearward. Thus, it will be seen from an inspection of Fig. 3 that a spring is 70 coiled around a peripherally grooved head 43

fixed to the end plate 19 of the auxiliary carriage. One end or arm 44 of this spring bears against a pin 45 projecting from said end plate 19, whereas the other end or arm 46 of the spring bears against a pin 47 projecting from the arm 5 or plate 34.

I have provided manually controlled means by which the feed rollers 30 on the auxiliary carriage may be shifted at will to and from effective position and may be held or retained in the ineffective position out of contactive engagement with the bill sheet B.

In the present instance these last mentioned means comprise the rock shaft 42 on which the feed rollers 41 are free to turn. This rock shaft 15 has an actuating crank arm 48 secured thereto at one end and which terminates in a finger piece 49. A second crank arm 50 also is secured to the rock shaft 42 and is pivoted at 51 to a link 52. This link in turn is pivoted to the arm 34 20 on a headed extension 53 of the pin 41 on the opposite side of the side plate 19, as shown in Figs. 1 and 2. The crank arm 50 has an extension or stop 54 that projects from the free end thereof and is adapted to coact with a stop pin 25 55 on the link 52 when the link and arm are brought into substantially a straight line position, as shown in Figs. 3 and 4. This occurs when the feed rollers 30 are shifted off to releasing position. At this time the spring 44, 46 is 30 exerting a force endwise on the members 52 and 50, which force is resisted by the shaft 42 and tends to hold the members 52 and 50 and the parts controlled thereby in the shifted position 35 with the feed rollers 30 released.

The extension 53 on the plate 34 also constitutes a pivotal support on which a gear wheel 56 is mounted to turn. This gear meshes with a pinion 57 secured to one end of the shaft 31 on which the feed rollers 30 are fixed. Motion 40 is thus transmitted to the shaft 31 and feed rollers 30 to feed a bill sheet B when said feed rollers press against the bill sheet or against the rollers 41 by which the sheet is supported.

A line spacing advance of a bill sheet B is effected by transmitting an intermittent step-by-step rotative movement to the gear 56. In the present instance this is brought about by manually controlled means carried wholly by the auxiliary carriage and consisting of a gear 58 that 50 meshes with the gear 56 and is riveted to a line spacing wheel 59 to turn therewith. These members 58 and 59 are mounted on and fixed to turn with a stub shaft 60 supported in the head 43 which is in the nature of a bearing bushing secured to the end plate 19. The shaft 60 is prolonged to the right at 61 beyond the hub 59a of the line spacing wheel, where it has a finger wheel 62 secured thereto. This finger wheel may be availed of to turn the gear 58 and, through 60 the intermediate train of connections, turn the feed rollers 30. The line spacing devices for intermittently turning the wheel 59 and thus turning the feed rollers 30 comprise a line spacing pawl 63 pivoted at 64 on a pawl carrier 65 mounted to turn freely on the hub 59a of the line spacing wheel, and therefore around the pivotal axis of the latter. The engaging nose of the line spacing pawl 63 normally rests on the curved face 66 of a shield 67 that determines at what 70 point in the throw of the line spacing pawl it will engage the line spacing wheel, thereby determining how much movement shall be given the line spacing wheel at each actuation of the pawl 63. To vary this amount the shield 19 75

mounted on the end plate 19 for adjustment in a circular path around the pivotal center of the wheel 59 by screw and slot connections 68^a and 68 respectively. A spring 69 is coiled around a 5 pin 10 on the pawl carrier 65 and is anchored at one end and bears down at its free end 69^a on the line spacing pawl 63 thus tending to force the engaging end of the latter towards the line spacing wheel and against the outer face of the 10 shield 66.

The pawl carrier 65 is intermittently actuated or rocked around its pivotal center 60 by the following means.

A link 71 is pivoted at one end, as at 72, to the 15 pawl carrier 65. The other end of this link is pivoted at 73 to a lever arm 74 which in turn is pivoted at 75 on the end plate 19 of the auxiliary carriage. A spring 76 is coiled around the pivot 75 of the lever 74 and is connected at one 20 end to a pin 77 on said lever and at the other end to a pin 78 on the end plate 19. The force of this spring is exerted to return the lever 74 and the parts connected therewith to the normal position, shown in Fig. 1, where they are arrested by 25 the pin 70 coacting with a stop pin 79 projecting from the outer face of the end plate 19, as shown in Figs. 1 and 2. The free end of the lever 74 carries a finger piece 80 by which it may be depressed. This will result in swinging the 30 pawl carrier 65 in an anti-clockwise direction, as the parts are shown in Fig. 1, during which movement the link 71 approaches a straight-line position with reference to the lever 74. The effect of this is to shift the end of the line spacing 35 pawl 63 off its shield 66 and permit it to engage the line spacing wheel and transmit movement to the feed rollers 30. Such motion continues until the back 63^a of the free end of the pawl coacts with a stop pin 81 (Fig. 1) projecting from 40 the end plate 19. This tends to wedge the pawl into more tenacious engagement with the line spacing wheel and arrest it and the pawl and prevent overthrow under the manual actuation of the parts.

It will be understood that the arm 34, by which 45 the gears 56 and 57 are carried, is pivoted on the stub shaft 60 on which the gear 58 and line spacing wheel 59 are mounted. It follows therefore that the arm 34 may receive a pivotal movement 50 with the arm 33 to control the movement of the feed rollers 30 into and out of effective position without altering the relation of the line spacing wheel 59, and gears 58, 56 and 57 relatively one to another, said gears remaining constantly in 55 mesh and effective whether the feed rollers be in the effective Fig. 1 position or in the ineffective Figs. 2 and 3 position. A spring-pressed roller detent 59^b coacts with the line spacing wheel 59 and is mounted on the arm 34 to swing therewith.

The usual line spacing mechanism including a 60 line spacing wheel 82 (Fig. 1) is employed for the platen 2 to advance the ledger sheet L and carbon sheet C but such mechanism has nothing whatever to do with the bill sheet B which is under independent control for line spacing advance movement by the feed rollers 30 actuated by the finger piece 80 or the finger wheel 62.

The end plate 19 has an upwardly extending 70 portion 83 that constitutes a finger piece situated conveniently adjacent to finger piece 80, so that the operator with one hand may grasp the finger piece 83 to shift the auxiliary carriage along to any desired position relatively to the platen carriage, at the same time having one finger of

the same hand available to actuate the line spacing lever 74.

In order that the auxiliary carriage may be readily shifted along the platen carriage to different predetermined selected positions, so that a vertical columnar field on the bill sheet may be brought successively to overlie different columnar fields on the ledger sheet, I have provided simple key controlled means that may be readily actuated to attain the ends specified and which will now be described.

Secured by screws 84 to the rear of the supporting bar 24, and spaced apart therefrom by washers 85, is a stop or locking bar 86 which extends throughout the length of the supporting bar. The upper edge of this stop bar is provided with locking notches 87 at intervals throughout the length thereof. Cooperating with the stop bar is a stop or locking member 88 carried at one end of a lever 89 pivoted at 90 to the side plate 19 of the auxiliary carriage. This lever extends forward and carries an off-set key 91 at its forward end, said key being located adjacent to the finger piece 83, so that the finger piece 91 may be manipulated by the same hand of the operator that grasps the finger piece 83 and operates the key 80. A contractile spring 92 is connected at one end to a pin 93 on the end plate 19 and at its other end to a pin 94 on the lever 89. The width of each notch 87 in the locking bar is such that the locking device 88 may seat itself therein, and when thus seated will hold the auxiliary carriage against movement along the platen carriage. A depression of the key 91 withdraws the locking device 88 from a notch 87 and after a slight shifting movement of the auxiliary carriage along the supporting bar has been effected the operator may release the key 91 and the locking device will bear on the upper edge portion 95 of the locking bar intermediate the notches 87 therein. When the auxiliary carriage has been moved far enough to bring the locking device 88 into register with the next notch 87 said device will be spring pressed into said notch and lock the auxiliary carriage against movement on the platen carriage. The operator then proceeds with the writing, the platen carriage and auxiliary carriage being locked to move together in the step-by-step letter space movements of the former.

Of course any desired notches 87 may be skipped over by the operator maintaining the finger key 91 depressed until about the time the auxiliary carriage has reached the desired position where the bill sheet has overlapped and registered with the proper column on the ledger sheet where entry is to be made. The key 91 may then be released by the operator and when exact registration has been effected the locking device 88 will be forced by its spring in the registering notch 87.

I have provided simple and effective visual indicating means so that the operator may know at all times what position the auxiliary carriage is in with reference to the platen carriage and the ledger sheet carried thereby. This is quite important inasmuch as the carbon sheet C may entirely cover the ledger sheet and the operator in the absence of the indicating means would not know the exact widthwise relation between a bill sheet and the ledger sheet. I will now describe the indicating means referred to.

The front face of the supporting bar 24 is grooved at 96 throughout its length to receive a thin sheet metal sheath 97 open at the front 75

thereof where it has overlapping edges 88, so as to retain and expose an indicating strip or scale 99. This strip may be covered with a transparent celluloid strip 100, both of the strips 99 and 100 being removable endwise from the sheath 97 when the bar 24 is detached from the end plates 13. The indices on the indicating strip preferably correspond to the headings of the different columns on the ledger sheet and to the location 10 thereof. This indicating strip may be conveniently provided by cutting a transverse strip including the column designations from a ledger sheet and inserting it in place in the sheath 97.

Coacting with the indices on the indicating strip 99 is a pointer or indicator 101 (Fig. 2) which is fixed to and projects to the left from the side plate 18 of the auxiliary carriage and coacts with the indices on the indicating strip to designate the columnar position of the auxiliary carriage and the bill sheet B carried thereby with reference to the platen carriage and the different columns on the ledger sheet carried thereby. For example, when the pointer is just to the right of the left-hand dividing line of the 25 column bearing the designation "City" on the index strip, then the auxiliary carriage will be positioned relatively to the platen carriage so as to hold the bill sheet in register with the "City" column d on the ledger sheet. In this 30 manner a manifold copy of the item written on the bill sheet at this time will be produced in the proper column on the ledger sheet. Of course it will be understood that when the auxiliary carriage is thus hand positioned with the aid of 35 the indicating devices referred to, the locking device 88 will be forced by its spring into a registering locking notch 87 and lock the auxiliary carriage to travel with the platen carriage in the step-by-step letter space movements of the 40 latter as the writing is being produced.

In the construction as thus far described it is necessary to cut the notches 87 in the locking bar to accord with the particular form of ledger sheet employed in each instance. However, inasmuch as one concern usually employs only one and the same character ledger sheet this special cutting of the locking bar is usually found sufficient. Nevertheless, in Figs. 6, 7 and 8 I have shown a modified form of locking bar construction, 50 or means employed in conjunction therewith, for enabling variations in the set-up to be effected to bring different notches 87 into use as may be desired. Said construction will now be described.

The locking bar 86 is, or may be, the same as 55 previously described with locking notches 87 therein at intervals throughout its length. A so-called shielding bar 102 is mounted on and arranged parallel with the locking bar by headed pins 103, the stems of which pass through horizontal slots 104 in the shielding bar and are secured to the locking bar. The bar 102 may therefore be shifted or adjusted longitudinally to any one of several given positions, three such positions being provided for in the present instance. 60 The bar 102 is locked or held in any one of said three positions by a detent 105 mounted on the free end of a leaf spring 106 secured at its opposite end by screws 107 to the locking bar 86. The detent is held under spring pressure in any one 65 of the three locking notches 108 in the bottom edge of the bar 102. The upper edge of the bar 102 is provided with notches 109 at different points along its length. The adjustment of the bar 102 will vary the notches 87 and 109 which 70 are brought into register, three different adjust- 75

ments of the bar 102 being shown in Figs. 6, 7 and 8, providing three setups where notches 87 and 109 are in register. In Fig. 6 the first, third and fifth notches 87 (counting from the left) are exposed for the entry of the locking member 88. In Fig. 7 the first, second, fourth and sixth notches 87 are thus exposed. In Fig. 8 the first and third notches 87 are thus exposed.

Of course it will be understood that when a full unnotched portion of the shielding bar 102 overlaps a notch 87 in the locking bar, said bar 102 will prevent the entry of the locking device 88 in the covered notch 87 thereby rendering it ineffective.

By these means a variation in the set-up of the locking means for the auxiliary carriage may be readily brought about without changing the locking bar.

In order that ready access may be had to the platen at both front and rear thereof for the ready introduction, adjustment and removal of the work sheets and more particularly the ledger sheet L and carbon sheet C, I provide a construction that enables the auxiliary carriage to be shifted from its normal position over the platen, as shown in full lines in Fig. 1, to an unobstructing position, indicated by the dotted line showing in the same view and also that enables the auxiliary structure as a whole to be applied to or detached from the machine.

Such construction involves the pivoting of the downwardly and forwardly projecting arms 110 of the end plates 13 of the supporting frame to the front of the platen carriage. Preferably this is effected in such a manner that the supporting frame with the auxiliary carriage and all of the remaining parts carried thereby may be detached from the machine, so that this entire auxiliary structure may be applied to or detached from the platen carriage as a single unit and in the nature of an attachment that may be applied to a standard machine.

A convenient manner of pivoting the supporting frame on the platen carriage is to provide a bearing opening in the end of each arm 110 to receive the usual rock shaft 111 by which the feed rollers 10 are controlled. This provides for swinging the supporting frame and the parts carried thereby from the full to the dotted line positions in Fig. 1 and vice versa, the weight of the parts maintaining the supporting frame in its full line position with the feed rollers 11 pressed by such weight against the platen and limiting the downward motion of the supporting frame.

In order to firmly connect the supporting frame at the rear thereof to the platen carriage and resist any side strain on said supporting frame I provide means which will now be described.

Each end plate 13 of the supporting frame is provided with a depending rearwardly extending arm 112 which at its lower end is received and guided between oppositely inclined faces 113 (Fig. 5) on collars 114. Each collar is secured by a set screw 115 on the usual cross bar or cross rod 116 that unites the end plates 117 of the platen carriage. The cam face 113 on each collar 114 joins a vertically disposed face 118. The distance between the parallel faces 118 on the two companion collars is about equal to the thickness of the lower end of the associated arm 112, so that said arm when in normal position is held snugly between such parallel faces and resists any lateral strain on the supporting frame at the rear side thereof. It will be observed from Figs. 1 and 5 that the lower end of each arm 112, when

in normal position, does not reach contact with the cross rod 116 and does not interfere with the weight of the supporting frame and the parts carried thereby applying the feed rollers 11 to 5 the platen.

Means are employed to limit the movement of the supporting frame to the dotted line position in Fig. 1. In the present instance such means comprise a pair of links 119 and 120 pivotally 10 united at their adjacent overlapping ends, as indicated at 121. The rear link 119 is pivoted at its lower end on the cross rod 116, whereas the lower end of the forward link 120 is pivoted on the cross rod 12 of the supporting frame, and on 15 which the feed rollers 11 are mounted. A stop pin 122 on the link 120 coacts with a projecting end 123 on the link 119 to limit the relative movement of the links as they approach a straight line position, as indicated in dotted lines in Fig. 1. 20 This prevents a dead centering of said links, and prevents a locking of the supporting frame in the dotted line position at the same time supporting it in such position and limiting its motion in this direction and holding the parts carried thereby out of contact with the machine frame and parts carried thereby.

It will be understood that by carrying the lower end of the bill sheet B in the unobstructed channel 9 between the deflectors 7 and 8 it is held free 30 from interference with its displacement with the auxiliary carriage along the platen carriage.

It is thought that the operation of the machine will be fully understood from the foregoing description it being understood that an independent 35 line spacing advance of the bill sheet is effected after the entry of every item thereon, whereas the manifold copies of such items are distributed in different columns along a single horizontal line on the ledger sheet.

40 While the shifting of the auxiliary carriage on the platen carriage, the line spacing of the bill sheet, etc., are entirely hand controlled, such operations may, nevertheless, be rapidly and accurately effected.

45 The bill sheet B shown in the present instance is a multiple form sheet comprising, say, four corresponding printed leaves or forms 124 united at adjacent edges 125 and having interleaved carbon sheets 126 disposed between the bill forms 50 124. The spaces for the entry of data on the various forms 124 of a multiple bill sheet are maintained in register so that an item entered in a given space on the first or outermost leaf will be duplicated as a manifold copy in a corresponding space on each of the other leaves, thus 55 giving four copies of a bill at a single writing in addition to corresponding entries on the ledger sheet.

I have not gone extensively into the detailed 60 manner of filling in each item on the bill and ledger sheets in the foregoing description as this varies widely depending on the character of the bill or the work to be done. In some instances part of the data is filled in on other 65 machines and in some instances items are subsequently filled in with pen and ink on the written bills. However, the single example given, and the description of the use of the machine in connection therewith is sufficient to arrive at a 70 clear understanding of one of the various uses to which the machine may be put.

The machine of the present invention has proved highly efficient in various fields in which it has been employed, and has proved highly 75 effective, rapid and accurate in operation in use

in connection with highly complicated tax bill entries of different kinds. It may be mentioned in this connection that with each machine of the present invention from 1200 to 1500 bills and extensions per day may be readily made; 5 that in a very brief time operators acquire such speed and that the machines give no trouble and have proved highly satisfactory from every point of view.

Although I have described in detail one form 10 or embodiment of my invention it should be understood that various changes may be made in the construction, and that parts thereof may be employed without others, without departing from my invention as it is defined in the accompanying claims. 15

What I claim as new and desire to secure by Letters Patent is:

1. The combination of a platen carriage, a 20 rotative cylindrical platen carried thereby, an auxiliary primary work sheet carrying carriage, means for mounting the latter on said platen carriage for movement therewith and for independent travel along said platen and platen carriage to different set positions and also for 25 movement thereon to enable said auxiliary carriage to be shifted to and from effective or operative position for use, and means carried by said auxiliary carriage for carrying a primary work sheet therewith in the independent 30 travel of said auxiliary carriage.

2. The combination of a platen carriage, a 35 rotative cylindrical platen carried thereby, an auxiliary primary work sheet carrying carriage, means for mounting said auxiliary carriage on said platen carriage for movement therewith and for independent traveling movement along the carriage and said platen as well as a swinging movement on the platen carriage to enable said auxiliary carriage by its swinging movement to be shifted to and from operative position and when in the last mentioned position to give access to paper on the platen carriage and to enable the auxiliary carriage by its independent traveling movement to bring the primary work sheet carried thereby to different points along said platen, means carried by said auxiliary carriage for carrying a work sheet therewith in the independent traveling and swinging movements of said auxiliary carriage, and paper feed rollers 50 carried by said auxiliary carriage mounting means and movable into and out of cooperation with the platen or a work sheet thereon by said swinging movement of the auxiliary carriage.

3. The combination of a platen carriage, a 55 platen carried thereby, a work sheet carrying auxiliary carriage, means for mounting the latter on said platen carriage for movement therewith and for independent travel along the platen carriage to different set positions and also for movement thereon to enable said auxiliary carriage to be shifted to and from effective or operative position, means for limiting the auxiliary carriage in its movement to and for supporting it in its inoperative position, and means carried by said auxiliary carriage for carrying a primary work sheet therewith in the independent travel of said auxiliary carriage.

4. The combination of a platen carriage, a 70 platen carried thereby, an auxiliary paper carrying carriage, means for mounting the latter on said platen carriage for movement therewith and for independent traveling and swinging movements thereon to enable said auxiliary carriage by its independent swinging movement to be 75

shifted to and from effective or operative position, and collapsible pivotally united links which are connected to said carriages and when straightened limit the movement of the auxiliary carriage to and support it in its operative position.

5. The combination of a platen carriage, a platen carried thereby, an auxiliary carriage, means for mounting the latter on said platen carriage for movement therewith for independent movement along the carriage and for independent swinging movement thereon to enable said auxiliary carriage by its independent swinging movement to be shifted to and from effective or operative position, means carried by said auxiliary carriage for carrying a primary work sheet therewith in the independent travel of said auxiliary carriage and guiding and holding means that are brought into action when 15 the auxiliary carriage is shifted to operative position to provide an interlocking engagement between the platen carriage and the mounting means for the auxiliary carriage which prevents a relative endwise displacement between them.

25. 6. The combination of a platen carriage, a platen carried thereby, an auxiliary carriage, means for mounting the latter on said platen carriage for movement therewith and for independent movement along the platen carriage to different set positions and also for movement thereon to enable said auxiliary carriage to be shifted to and from effective or operative position, paper feed rollers carried by said auxiliary carriage, and means carried by said auxiliary 30 carriage for turning said feed rollers independently of the platen.

7. The combination of a platen carriage, a platen carried thereby, an auxiliary work sheet carrying carriage, means for mounting the latter on said platen carriage for movement therewith and for independent movement along the platen carriage to different set positions and also for movement thereon to enable said auxiliary carriage to be shifted to and from effective or operative position, two sets of cooperative feed rollers carried by said auxiliary carriage and maintained out of cooperative relation with the platen, and means operable at will for effecting a relative shifting of said feed rollers out of cooperative relation and for locking them in such condition.

55. 8. The combination of a platen carriage, a platen carried thereby, an auxiliary carriage, means for mounting the latter on said platen carriage for movement therewith and for independent movement along the platen carriage to different set positions and also for movement thereon to enable said auxiliary carriage to be shifted to and from effective or operative position, two sets of cooperative feed rollers carried by said auxiliary carriage and maintained out of cooperative relation with the platen, means operable at will for effecting a relative shifting of said feed rollers out of cooperative relation and for locking them in such condition, and manually controlled line spacing means carried by said auxiliary carriage and operable at will for actuating one set of said feed rollers.

70. 9. The combination of a platen carriage, a platen carried thereby, an auxiliary carriage, means for mounting the latter on said platen carriage for movement therewith and for independent movement along the platen carriage to different set positions and also for movement 75 thereon to enable said auxiliary carriage to be

shifted to and from effective or operative position, two sets of cooperative feed rollers maintained out of cooperative relation with the platen, means operable at will for effecting a relative shifting of said feed rollers out of cooperative relation and for locking them in such condition, manually controlled line spacing means carried by said auxiliary carriage and operable at will for actuating one set of said feed rollers, and a third set of paper feed rollers carried by said mounting means for the auxiliary carriage and movable thereby into and out of cooperation with the platen or a work sheet thereon.

10. The combination of a platen carriage, a cylindrical platen carried thereby, an auxiliary carriage, means for mounting said auxiliary carriage on said platen carriage for movement therewith and for independent movement along the platen carriage to different set positions and also for movement thereon to enable said auxiliary carriage to be shifted to and from operative position and when in the last mentioned position to give access to paper on the platen carriage, paper feed rollers carried by said mounting means for the auxiliary carriage and movable thereby into and out of cooperation with the platen or a work sheet thereon, an additional set of feed rollers carried by said auxiliary carriage and maintained out of cooperative relation with the platen and free from control thereby, and manually controlled means carried by the auxiliary carriage and operable at will for turning said last mentioned feed rollers to advance a work sheet independently of the platen.

15. 11. The combination of a carriage, a line spacing wheel carried thereby, a carrier pivoted for shifting movement around the axis of said line spacing wheel, paper feed rollers mounted on said carrier for shifting movement thereby into and out of effective position, intermediate constantly maintained driving connections between said line spacing mechanism and said feed rollers, and means with which said feed rollers coact to effect a feed of a work sheet.

20. 12. The combination of a carriage, a platen carried thereby, a line spacing wheel, a carrier pivoted for shifting movement around the axis of the line spacing wheel, paper feed rollers carried by said carrier and maintained at all times out of contactive engagement with the platen, intermediate constantly maintained driving connections between said line spacing wheel and said feed rollers for turning the latter and advancing a work sheet independently of the platen, intermittently actuated means turning said line spacing wheel, means operable at will for shifting said carrier to control the movement of said feed rollers into and out of effective position, and means with which said feed rollers coact to effect a feed of a work sheet.

25. 13. The combination of a platen carriage, a platen carried thereby, a line spacing wheel, a carrier pivoted for shifting movement around the axis of the line spacing wheel, paper feed rollers carried by said carrier and maintained at all times out of contactive engagement with the platen, intermediate constantly maintained driving connections between said line spacing wheel and said feed rollers for turning the latter and advancing a work sheet independently of the platen, intermittently actuated means turning said line spacing wheel, means operable at will for shifting said carrier to control the movement of said feed rollers into and out of effective position, an auxiliary carriage,

- means that enable the auxiliary carriage to travel with and to receive a traveling movement on the platen carriage and independently thereof, said feed rollers, line spacing wheel, 5 and intermediate driving connections being carried by said auxiliary carriage, and means with which said feed rollers coact to effect a feed of a work sheet.
14. The combination of a platen carriage, a 10 cylindrical platen carried thereby, a cross bar that extends throughout the length of the platen carriage, means for supporting said cross bar above the platen on said platen carriage, an auxiliary primary work sheet carrying carriage 15 mounted on said cross bar to travel with the platen carriage and to travel along said bar to different positions longitudinally of the platen carriage and throughout the length thereof, and means on said auxiliary carriage for supporting 20 and feeding separate work sheets past the printing line on the platen.
15. The combination of a platen carriage, a 25 cylindrical rotative platen carried thereby, a cross bar that extends substantially parallel with the axis of the platen and throughout the length of said platen, means for supporting said cross bar in normal position above said platen and for shifting movement transversely of the length of the cross bar from its normal position to afford access to the platen, an auxiliary work sheet carrying carriage mounted on said cross bar for independent traveling movement along the same and along said platen to different set positions and for shifting movement 30 with the bar as the latter is shifted from normal position above the platen, and means carried by said auxiliary carriage for carrying a primary work sheet therewith in the independent travel of said auxiliary carriage.
- 40 16. The combination of a platen carriage, a cylindrical rotative platen carried thereby, a cross bar that extends substantially parallel with the axis of the platen and throughout the length thereof, means for supporting said cross 45 bar in normal position above said platen and for shifting movement transversely of the length of the cross bar from its normal position to afford access to the platen, an auxiliary work sheet carrying carriage mounted on said cross bar for independent traveling movement along the same and along said platen to different set positions and for shifting movement with the bar as the latter is shifted from normal position 50 above the platen, manually controlled means for locking said auxiliary carriage in different predetermined columnar positions to which it may be shifted along said cross bar, and means carried by said auxiliary carriage for carrying a primary work sheet therewith in the independent travel of said auxiliary carriage.
- 55 17. The combination of a platen carriage, a cylindrical rotative platen carried thereby, a frame pivoted on said carriage, a cross bar carried by and forming part of said frame, an auxiliary work sheet carrying carriage mounted on said cross bar for independent traveling movement along it to different columnar positions above said platen and for pivotal movement with said frame to give access to the platen, and 60 means carried by said auxiliary carriage for carrying a primary work sheet therewith in the independent travel of said auxiliary carriage.
- 70 18. The combination of a platen carriage, a cylindrical platen carried thereby, a frame pivoted on said carriage for movement thereon to 75 and from normal position, a cross bar carried by said frame and forming part thereof, paper feed rollers carried by said frame and moved thereby into contact with the platen when the frame is shifted to normal position and moved thereby out of contact with the platen when the frame is shifted from normal position, an auxiliary work sheet carrying carriage mounted on said cross bar for independent traveling movement along it to different columnar positions, and means carried by said auxiliary carriage for carrying a primary work sheet therewith in the independent travel of said auxiliary carriage.
19. The combination of a platen carriage, a 10 platen carried thereby, a cross bar that extends throughout the length of the carriage, means for fixedly supporting said cross bar above the platen on said platen carriage and for affording a swinging movement of said cross bar in a direction transverse to the length of said bar, an auxiliary work sheet carrying carriage mounted 15 on said cross bar to travel with the platen carriage and for traveling movement along said bar to different positions longitudinally of the platen carriage throughout the length thereof, means 20 carried wholly by said auxiliary carriage for carrying and feeding separate work sheets to the printing line on the platen, a scale carried by said cross bar, and indicating means carried by said auxiliary carriage and cooperative with said 25 scale.
20. The combination of a platen carriage, a cylindrical rotative platen carried thereby and extending substantially throughout the length of the carriage, a cross bar that extends 30 throughout the length of the carriage, means for supporting said cross bar above the platen on said platen carriage and for swinging movement into and out of normal position, an auxiliary work sheet carrying carriage mounted on 35 said cross bar to travel with the platen carriage and for independent traveling movement along said bar to different positions longitudinally of the platen carriage and throughout the length of the platen, means carried by the auxiliary 40 carriage for feeding separate primary or outside work sheets to the printing line on said platen, a stop bar carried by said cross bar, and a key controlled stop carried by said auxiliary carriage and which coacts with said stop bar to 45 lock the auxiliary carriage to the platen carriage in different predetermined positions thereon.
21. The combination of a platen carriage, a cylindrical rotative platen carried thereby and extending throughout the length thereof, a cross 50 bar having a groove in the front face thereof, an indicating scale seated in and removable from said groove, means for supporting said cross bar above the platen on said platen carriage and for swinging movement transversely of the length of said bar, an auxiliary work sheet carrying carriage mounted on said cross bar to travel with the platen carriage and for traveling movement along said bar to different positions longitudinally and throughout the length of the platen carriage, and an indicator carried by said auxiliary carriage and cooperative with said scale.
22. The combination of a platen carriage, a cylindrical platen carried thereby, a frame pivoted on said carriage, a cross bar carried by and forming part of said frame, an auxiliary carriage mounted on said cross bar for shifting movement along it to different columnar positions above the platen and for pivotal movement

- with said frame to give access to the platen, paper feed rollers carried by said auxiliary carriage and maintained at all times out of contact with the platen, and means carried by said auxiliary carriage for turning said feed rollers independently of the platen for advancing a work sheet independently thereof. 5
23. The combination of a platen carriage, a cylindrical rotative platen carried thereby, a frame pivoted on said carriage, a cross bar carried by, fixed to, and forming part of said frame and extending throughout the length of said platen, a primary work sheet carrying auxiliary carriage mounted on said cross bar for traveling movement along it to different columnar positions above and throughout the length of said platen and for pivotal movement with said frame to give access to the platen, a locking bar carried by said frame, a key controlled locking member 10 carried by said auxiliary carriage for locking the auxiliary carriage at any one of a plurality of predetermined positions on and throughout the length of the platen carriage to travel therewith, and means carried by said auxiliary carriage for holding a work sheet to travel therewith. 15
24. The combination of a platen carriage, a cylindrical platen carried thereby, a frame pivoted on said carriage, a cross bar carried by and forming part of said frame, an auxiliary carriage mounted on said cross bar for shifting movement along it to different columnar positions above the platen and for pivotal movement with said frame to give access to the platen, a line spacing wheel mounted on said auxiliary carriage, paper feed rollers mounted on said auxiliary carriage, intermediate driving connections between said line spacing wheel and said feed rollers, and means carried by said auxiliary carriage for actuating said line spacing wheel. 20
25. The combination of a carriage, a key controlled stop member carried thereby, a locking bar having a plurality of notches in any one of which said key controlled stop is adapted to be seated to lock said carriage and bar against relative movement, a notched shielding bar cooperative with said locking bar to close certain of the notches therein and open others, and means for affording an adjustment of said shielding bar to determine the notches in the locking bar that are left open and thus vary the notches that are rendered effective. 25
26. The combination of a carriage, a key controlled stop member carried thereby, a locking bar having a plurality of notches in any one of which said key controlled stop is adapted to be seated to lock said carriage and bar against relative movement, a notched shielding bar cooperative with said locking bar to close certain of the notches therein and open others, the relative arrangement of the notches in the two bars being such that different notches are exposed in the locking bar depending on the longitudinal adjustment of the shielding bar relatively thereto, and means for affording such an adjustment of the shielding bar and for holding it against accidental displacement from its adjusted position. 30
27. The combination of a carriage, a key controlled stop member carried thereby, a locking bar having a plurality of notches in any one of which said key controlled stop is adapted to be seated to lock said carriage and bar against relative movement, a shielding bar arranged parallel with and mounted for adjustment longi- 35
- tudinally of said locking bar, said shielding bar having a series of notches therein located differently from the notches in the locking bar and so disposed that different notches in the locking bar will be maintained open for coaction with said stop member depending on the adjustment of said shielding bar, and detent means for holding said shielding bar in any one of several given positions and thus determine the notches in the locking bar that are rendered effective. 5
28. The combination of a platen carriage, a cylindrical rotative platen carried thereby and extending throughout the length of the carriage, an auxiliary work-sheet-carrying carriage carried by the platen carriage and when in operative position arranged above the platen, means for mounting said auxiliary carriage for travel as a single unit on and for manual displacement in either direction along the platen carriage parallel with the axis of the platen and throughout the length thereof for correlating a work sheet carried by the auxiliary carriage with a work sheet carried on said cylindrical platen, manually controlled means for temporarily locking said auxiliary carriage in any one of a number of different given positions to which it may travel and be displaced along said platen carriage, line spacing means for rotating the platen, and intermittently operated independently actuated means carried by and travelling with said auxiliary carriage for line spacing separate work sheets on the auxiliary carriage without affecting the means for controlling the work sheet on the platen. 10
29. The combination of a platen carriage, a cylindrical rotative platen carried thereby and extending throughout the length thereof, an auxiliary work-sheet-carrying carriage carried by the platen carriage and arranged above said platen, means for mounting said auxiliary carriage for manual displacement in either direction along the platen carriage parallel with the axis and throughout the length of the platen, manually controlled means for locking said auxiliary carriage in any one of a number of different given positions to which it may be displaced along said platen carriage, means that enable said auxiliary carriage to receive a bodily shifting movement away from its normal position above the platen to an unobstructing position, thereby affording access to the platen for the ready introduction of work sheets thereto, and means carried by said auxiliary carriage for holding a work sheet to travel therewith. 15
30. The combination of a platen carriage, a rotative cylindrical platen carried thereby that extends throughout the length of the carriage, a supporting frame pivoted to said carriage for swinging movement thereon from a normal position over the platen to an unobstructing position remote therefrom, a work-sheet-carrying auxiliary carriage carried by said frame and mounted thereon for independent traveling movement longitudinally of the axis and throughout the length of the platen and also for swinging movement with said frame to an unobstructing position, and means carried by said auxiliary carriage for carrying a primary work sheet therewith in the independent travel of said auxiliary carriage. 20
31. The combination of a platen carriage, a cylindrical platen carried thereby, a supporting frame pivoted to said carriage for swinging movement thereon from a normal position over the platen to an unobstructing position remote therefrom, a work-sheet-carrying auxiliary car- 25

- riage carried by said frame and mounted thereon for shifting movement longitudinally of the axis and throughout the length of the platen and also for swinging movement with said frame 5 to an unobstructed position, and manually controlled intermittently actuated line spacing means carried wholly by said auxiliary carriage and shiftable therewith to unobstructing position.
- 10 32. The combination of a platen carriage, a cylindrical platen carried thereby, a supporting frame pivoted to said carriage for swinging movement thereon from a normal position over the platen to an unobstructing position remote 15 therefrom, a work-sheet-carrying auxiliary carriage carried by said frame and mounted thereon for independent traveling movement longitudinally of the axis of the platen and also for swinging movement with said frame to an unobstructing position, paper feed rollers carried 20 by said frame and movable thereby into contact with the platen when the frame is shifted to normal position and moved away from the platen when said frame is shifted to unobstructing 25 position, and means carried by said auxiliary carriage for carrying a primary work sheet therewith in the independent travel of said auxiliary carriage.
33. The combination of a platen carriage, a cylindrical rotative platen carried thereby, a supporting frame pivoted to and extending throughout the length of said carriage at the front of the machine for fore and aft swinging movement thereon from a normal position over 35 the platen to an unobstructing position forward thereof, a cross bar fixed to said frame and arranged parallel with the axis of the platen and extending throughout the length of said platen, an auxiliary work - sheet - carrying carriage 40 mounted on said cross bar for manual movement along it to different selected positions throughout the length of said platen and when in effective position located above the platen, said auxiliary carriage being shiftable with said frame 45 to an unobstructing position in front of the platen, and means carried by said auxiliary carriage for holding a work sheet to travel therewith.
34. The combination of a platen carriage, a 50 rotative cylindrical platen carried thereby, a supporting frame that extends throughout the length of and is pivoted to said carriage at the front of the machine for fore and aft swinging movement thereon from a normal position over 55 the platen to an unobstructing position forward thereof, a cross bar fixed to said frame and arranged parallel with the axis of the platen and extending throughout the length of said platen, an auxiliary primary work-sheet-carrying carriage 60 mounted on said cross bar for manual movement along it to different selected positions throughout the length of said platen and when in effective position located above the platen, said auxiliary carriage being shiftable with said frame 65 to an unobstructing position in front of the platen, a key controlled locking member carried by the auxiliary carriage, means coacting therewith for locking said auxiliary carriage in any selected position to which it may be shifted along said cross bar, and means carried by 70 said auxiliary carriage for holding a work sheet to travel therewith.
35. The combination of a platen carriage, a cylindrical platen carried thereby, a supporting frame pivoted to said carriage at the front of 75 the machine for fore and aft swinging movement thereon from a normal position over the platen to an unobstructing position forward thereof, a cross bar secured to said frame and arranged parallel with the axis of the platen, an auxiliary work-sheet-carrying carriage mounted on said cross bar for manual movement along it to different selected positions and when in effective position located above the platen, said auxiliary carriage being shiftable with said frame to an unobstructing position in front of the platen, and manually controlled cooperative paper feed rollers carried by said auxiliary carriage for feeding a work sheet carried thereby independently of the platen, said feed rollers being shiftable to unobstructing position with the auxiliary carriage. 10
36. The combination of a platen carriage, a cylindrical platen carried thereby, a supporting frame pivoted to said carriage at the front of the machine for fore and aft swinging movement thereon from a normal position over the platen to an unobstructing position forward thereof, a cross bar secured to said frame and arranged parallel with the axis of the platen, an auxiliary work-sheet-carrying carriage mounted on said cross bar for manual movement along it to different selected positions and when in effective position located above the platen, said auxiliary carriage being shiftable with said frame to an unobstructing position in front of the platen, manually controlled paper feed rollers carried by said auxiliary carriage for feeding a work sheet carried thereby independently of the platen, said feed rollers being shiftable to unobstructing position with the auxiliary carriage, hand controlled means carried by said auxiliary carriage for releasing said feed rollers, and paper feed rollers carried by said frame and shiftable by the latter into and out of contact with the platen when said frame is moved respectively to and from obstructing position. 15
37. The combination of a platen carriage, a cylindrical platen carried thereby, a supporting rail or cross bar that is carried by said carriage and arranged above the platen and extends substantially throughout the length of the platen carriage and platen, an auxiliary carriage, roller bearings for supporting said auxiliary carriage for free movement along said supporting rail or cross bar, hand controlled means for locking said auxiliary carriage in any one of a plurality of positions to which it may be moved along said supporting rail, and means carried by said auxiliary carriage for carrying and feeding separate work sheets independently of the platen, whereby a work sheet thus carried by the auxiliary carriage may be rapidly moved therewith along the platen for correlating it relatively to a work sheet on the platen and said first mentioned work sheet may be fed independently of the work sheet on the platen. 20
38. A machine for typing amounts in a single vertical column on a non-continuous relatively narrow outside bill sheet and at the same time manifolding said amounts in a single horizontal line across a relatively wide record sheet, said machine including a cylindrical platen and a platen carriage for carrying an inner relatively wide record sheet, a trackway above said platen and extending substantially throughout the length thereof, a bill sheet carrying carriage or truck mounted to travel with said platen carriage and also to travel independently thereof along said trackway to different positions lon- 25

- 5 longitudinally of the platen and substantially throughout the length thereof for collating a single vertical bill-sheet-column with different columns spaced across the relatively wide inner record sheet, means for supporting an outside non-continuous bill sheet on said bill sheet carriage to travel with and relatively to the platen carriage and the inside record sheet carried thereby, and means for feeding the non-continuous bill sheet for line spacing in the single vertical column thereon. 5
- 10 39. A machine for typing amounts in a single vertical column on a bill sheet and at the same time manifolding said amounts in a single horizontal line across a record sheet, including a cylindrical platen and a platen carriage for carrying a record sheet, a trackway above said platen and extending substantially throughout the length thereof, a bill sheet carrying carriage or truck mounted to travel with said platen carriage and also to travel along said trackway to different positions longitudinally of the platen substantially throughout the length thereof for collating a single vertical bill-sheet-column with 15 different columns spaced across the record sheet, and means for supporting a non-continuous outside bill sheet on said bill sheet carriage to travel therewith relatively to the platen and to an inside record sheet carried thereby, said supporting means comprising an upright supporting member arranged above the platen at the front thereof for cooperation with the outside non-continuous bill sheet extending downward and rearward therefrom at the front of and beneath the 20 platen. 25
- 20 40. A machine for typing amounts in a single vertical column on a bill sheet and at the same time manifolding said amounts in a single horizontal line across a record sheet, including a platen and a platen carriage for carrying a record sheet, a trackway arranged above said platen and extending substantially throughout the length thereof, a bill sheet carrying carriage or truck mounted to travel with said platen carriage and 25 to travel along said trackway to different positions longitudinally of the platen substantially throughout the length thereof for collating the vertical bill-sheet-column with different columns spaced across the record sheet, and means for supporting a non-continuous outside bill sheet on 30 said bill sheet carriage to travel therewith relatively to the platen carriage and to an inside record sheet carried thereby, said supporting means comprising upright supporting members arranged above the platen at the front thereof for cooperation with the outside non-continuous bill sheet extending downward and rearward therefrom at the front of and beneath the platen, and means for affording a relative adjustment 35 between said supporting members towards and away from one another in order to coact with bill sheets of different widths. 40
- 35 41. A machine for typing amounts in a single vertical column on a non-continuous outside bill sheet and at the same time manifolding said amounts in a single horizontal line across an inner record sheet, said machine including a platen and platen carriage for carrying the record sheet, a trackway arranged above said platen and extending substantially throughout the length thereof, a bill sheet carrying carriage or truck mounted to travel with said platen carriage and also to travel along said trackway to different positions longitudinally of the platen substantially throughout the length thereof for 45 collating a single vertical bill-sheet-column with different columns spaced across the record sheet, means for supporting the bill sheet on said bill sheet carriage to travel therewith relatively to and along the platen and the record sheet car- 50 55 60 65 70 75
- 5 collating a single vertical bill-sheet-column with different columns spaced across the inside record sheet, means for supporting the outside non-continuous bill sheet on said bill sheet carriage to travel therewith relatively to the platen carriage and to the inside record sheet carried thereby, feed rollers carried by said bill sheet carrying carriage and cooperative with the bill sheet but free from contact with the platen and the record sheet carried by the platen carriage, and intermittently actuated means for turning said feed rollers. 10
- 15 42. A machine for typing amounts in a single vertical column on a bill sheet and at the same time manifolding said amounts in a single horizontal line across a record sheet, including a platen and a platen carriage for carrying a record sheet, a trackway arranged above said platen and extending substantially throughout the length thereof, a bill sheet carrying carriage or truck mounted to travel with said platen carriage and also to travel along said trackway to different positions longitudinally of the platen and substantially throughout the length thereof for collating a single vertical bill-sheet-column with different columns spaced across the record sheet, co-acting feed rollers carried by said bill sheet carrying carriage and cooperative with an intermediate non-continuous outside bill sheet but free from contact with the platen and the record sheet carried by the platen carriage, means for maintaining contactive engagement between said feed rollers, means for separating said feed rollers and for maintaining them separated indefinitely, and intermittently actuated means for turning said feed rollers. 20 25 30 35
- 40 43. A machine for typing amounts in a single vertical column on a bill sheet and at the same time manifolding said amounts in a single horizontal line across a record sheet, including a platen and a platen carriage for carrying a record sheet, a trackway arranged above said platen and extending substantially throughout the length thereof, a bill sheet carrying carriage or truck mounted to travel with said platen carriage and also to travel along said trackway to different positions longitudinally of the platen and substantially throughout the length thereof for collating a single vertical bill-sheet-column with different columns spaced across the record sheet, means for supporting a non-continuous bill sheet on said bill sheet carriage to travel therewith relatively to the platen carriage and the record sheet carried thereby, feed rollers carried by said bill sheet carrying carriage and cooperative with the bill sheet but free from contact with the platen and the record sheet carried by the platen carriage, and hand controlled intermittently actuated means for turning said feed rollers. 45 50 55 60
- 65 44. A machine for typing amounts in a single vertical column on a bill sheet and at the same time manifolding said amounts in a single horizontal line across a record sheet, including a platen and a platen carriage for carrying a record sheet, a trackway arranged above said platen and extending substantially throughout the length thereof, a bill sheet carrying carriage or truck mounted to travel with said platen carriage and also to travel along said trackway to different positions longitudinally of the platen for collating a single vertical bill-sheet-column with different columns spaced across the record sheet, means for supporting the bill sheet on said bill sheet carriage to travel therewith relatively to and along the platen and the record sheet car- 70 75

ried thereby, cooperative feed rollers carried by said bill sheet carrying carriage and cooperative with an outside non-continuous bill sheet but free from contact with the platen and the inside 5 record sheet carried by the platen carriage, spring means for maintaining contactive engagement between said feed rollers, means for separating said feed rollers and for maintaining them separated indefinitely and intermittently 10 actuated means for turning said feed rollers.

45. A machine for typing amounts in a single vertical column on a bill sheet and at the same time manifolding said amounts in a single horizontal line across a record sheet, including a 15 platen and a platen carriage for carrying a record sheet, a trackway arranged above said platen and extending substantially throughout the length thereof, a bill sheet carrying carriage or truck mounted to travel with said platen carriage 20 and also to travel along said trackway to different positions longitudinally of the platen for collating a single vertical bill-sheet-column with different columns spaced across the record sheet, means for supporting a non-continuous outside 25 bill sheet on said bill sheet carriage to travel therewith relatively to the platen carriage and an inside record sheet carried thereby, said supporting means comprising upright supporting members arranged above the platen at the front 30 thercof for cooperation with a bill sheet extending downward and rearward at the front of and beneath the platen, paper feed rollers carried by said bill sheet carriage and cooperative with said outside bill sheet, and means for affording a relative adjustment between said supporting members 35 towards and away from one another in order to coat with bill sheets of different widths.

46. A machine for typing amounts in a single vertical column on a bill sheet and at the same time manifolding said amounts in a single horizontal line across a record sheet, including a 40 platen and a platen carriage for carrying a record sheet, a trackway arranged above said platen and extending substantially throughout the 45 length thereof, a bill sheet carrying carriage or truck mounted to travel with said platen carriage and also to travel along said trackway to different positions longitudinally of the platen for collating a single vertical bill-sheet-column with different 50 columns spaced across the record sheet, means for supporting a non-continuous outside bill sheet on said bill sheet carriage to travel therewith relatively to the platen carriage and the inside record sheet carried thereby, said supporting 55 means comprising upright supporting members arranged above the platen at the front thereof for cooperation with a bill sheet extending downward and rearward at the front of and beneath the platen, a side edge guide carried by each of said 60 supporting members, and means for affording a relative adjustment between said supporting members towards and away from one another in order to coat with bill sheets of different widths.

47. A machine for typing amounts in a single 65 vertical column on a bill sheet and at the same time manifolding said amounts in a single horizontal line across a record sheet, including a platen and a platen carriage for carrying a record sheet, a trackway arranged above said platen 70 and extending substantially throughout the length thereof, a bill sheet carrying carriage or truck mounted to travel with said platen carriage and also to travel along said trackway to different positions longitudinally of and over the platen 75 for collating a single vertical bill-sheet-column

with different columns spaced across the record sheet, means for supporting a non-continuous outside bill sheet on said bill sheet carriage to travel therewith relatively to the platen carriage and the record sheet carried thereby, said supporting means comprising an upright supporting member arranged above the platen at the front thereof for cooperation with a bill sheet inserted rearward and downward from the front of and beneath the platen, and means for affording a shifting of said supporting member in a direction transverse to the line of travel thereof with said platen carriage. 5

48. A machine for typing amounts in a single vertical column on a bill sheet and at the same time manifolding said amounts in a single horizontal line across a record sheet, including a 15 platen and a platen carriage for carrying a record sheet, a trackway arranged above said platen and extending substantially throughout the 20 length thereof, a bill sheet carrying carriage or truck mounted to travel with said platen carriage and also to travel along said trackway to different positions longitudinally of and over the platen for collating the vertical bill-sheet-column with different columns spaced across the record sheet, means for supporting an outside non-continuous bill sheet on said bill sheet carriage to travel therewith relatively to the platen carriage and an inside record sheet carried thereby, and key controlled columnar tabulator mechanism for arresting the relative travel of the bill sheet carrying carriage in different columnar fields corresponding to the different vertical columns on the record sheet, so that the single vertical column on the outside bill sheet may be brought into register with each of said vertical columns on the inside record sheet. 30

49. A machine for typing amounts in a single vertical column on a bill sheet and at the same time manifolding said amounts in a single horizontal line across a record sheet, including a cylindrical platen and a platen carriage for carrying a record sheet, a trackway arranged above said platen and extending substantially throughout the length thereof, a bill sheet carrying carriage or truck mounted to travel with said platen carriage and also to travel along said trackway to different positions longitudinally of and over the platen for collating a single vertical bill-sheet 45 column with different columns spaced across the record sheet, means for supporting an outer non-continuous bill sheet on said bill sheet carriage to travel therewith relatively to the platen carriage and an inside record sheet carried thereby, a plurality of arresting means for arresting the relative travel of the bill sheet carrying carriage in different columnar positions corresponding to the different vertical columns on the record sheet, and a key controlled stop member carried by the bill sheet carrying carriage and having an interlocking engagement with each of said arresting means to prevent a displacement of the bill carrying carriage relatively to the platen carriage in either direction of its travel. 50

50. A machine for typing amounts in a single vertical column on a bill sheet and at the same time manifolding said amounts in a single horizontal line across a record sheet, including a cylindrical platen and a platen carriage for carrying a record sheet, a trackway arranged above said platen and extending substantially throughout the length thereof, a bill sheet carrying carriage or truck mounted to travel with said platen carriage and also to travel along said trackway to 65

different positions longitudinally of and over the platen for collating a single vertical bill-sheet-column with different columns spaced across the record sheet, means for supporting an outside 5 non-continuous bill sheet on said bill sheet carriage to travel therewith relatively to the platen carriage and an inside record sheet carried thereby, and key controlled columnar tabulator mechanism for arresting the relative travel of the bill 10 sheet carrying carriage in different columnar fields corresponding to the different vertical columns on the record sheet, so that the single vertical column on the bill sheet may be brought into register with each of said vertical columns on 15 the record sheet, said tubulator mechanism comprising a key, and a stop member spring pressed to effective position and released therefrom by an actuation of said key.

51. A machine for typing amounts in a single 20 vertical column on a bill sheet and at the same time manifolding said amounts in a single horizontal line across a record sheet, including a cylindrical platen and a platen carriage for carrying a record sheet, a trackway arranged above 25 said platen and extending substantially throughout the length thereof, a bill sheet carrying carriage or truck mounted to travel with said platen carriage and to travel along said trackway to different positions longitudinally of and over the 30 platen for collating a single vertical bill-sheet-column with different columns spaced across the record sheet, means for supporting a non-continuous outside bill sheet on said bill sheet carriage to travel therewith relatively to the platen carriage and an inside record sheet carried thereby, and key controlled columnar tabulator mechanism for arresting the relative travel of the bill sheet carrying carriage in different columnar fields corresponding to the different vertical 35 columns on the record sheet, so that the single vertical column on the bill sheet may be brought into register with each of said vertical columns on the record sheet, said tabulator mechanism comprising a plurality of column determining 40 means, a coacting stop member, means by which said coacting stop member is caused to automatically engage each of said column determining means when it registers therewith, and a key for releasing said coacting stop member from such 45 engagement.

52. In a typewriting machine having a printing-field, the combination with a paper-carriage for carrying a record-sheet across which are to be typed a plurality of item-columns, said carriage movable in column-tabulating direction past 55 said printing-field, of a trackway on said carriage extending in the direction of column-spacing, a truck having a paper-table supported by and shiftable along said trackway, and means 60 cooperative with said table to hold another work-sheet superposed on the record sheet at the printing-field, said means including a device for holding said other sheet against said table, said trackway and said table being disposed so as to clear 65 the printing-field, the shift of said paper-table on said trackway being operative to collate said other sheet with any record-sheet column.

53. In a typewriting machine having a printing-field, the combination with a paper-carriage 70 and platen for carrying a record-sheet across which are to be typed a plurality of item-columns, said carriage movable in column-tabulating direction past said printing field, of a trackway on said carriage above the platen and extending in 75 the direction of column-spacing, a truck having

a paper-table, said truck being supported by and shiftable along said trackway above the platen, and means on said truck for holding another work-sheet superposed on the record-sheet at the printing-field while said other sheet is also supported on said table, said trackway and said table being disposed so as to clear the printing-field, the shift of said paper-table along said trackway being operative to collate said other sheet with any record-sheet column. 10

54. In a typewriting machine having a printing-field, the combination with a paper-carriage and platen for carrying a record-sheet across which are to be typed a plurality of item-columns, said carriage movable in column-tabulating direction past said printing-field, of a trackway on said carriage extending in the direction of column-spacing, a truck having a paper-table, said truck being supported by and shiftable along said trackway above said platen, and means on said truck for holding another work-sheet superposed on the record-sheet at the printing field, said means also holding said other sheet on said table, said trackway and said table being disposed so as to clear the printing-field, the shift of said truck and paper-table on said trackway being operative to collate said other sheet with any record-sheet column, means being provided whereby said table may be moved transversely of said tabulating direction. 20

55. The combination of a platen carriage, a cylindrical rotative platen carried thereby and extending substantially throughout the length of said carriage, an auxiliary work-sheet carrying carriage carried by the platen carriage above the platen, means for mounting said auxiliary carriage for travel as a single unit on and for displacement in either direction along the platen carriage parallel with the axis of the platen and throughout the length thereof for 30 correlating a non-continuous outside work sheet carried by the auxiliary carriage with an inside work sheet carried on said cylindrical platen, means for temporarily locking said auxiliary carriage in any one of a number of different given 40 positions to which it may travel on and for displacing it along said platen carriage, paper feed rollers carried by said auxiliary carriage and coacting only with the outside work sheet carried thereby, and intermittently actuated means for 50 turning said feed rollers to line space the work sheet carried by the auxiliary carriage. 45

56. The combination of a platen carriage, a cylindrical rotative platen carried thereby and extending substantially throughout the length of said carriage and cooperative with an inside work sheet, a cross bar that extends throughout the length of the carriage, means for supporting said cross bar on said platen carriage above the platen, an auxiliary work sheet carriage mounted on said 55 cross bar to travel with the platen carriage and for independent traveling movement along said cross bar to different positions longitudinally of and over the platen, means on the auxiliary carriage for supporting and feeding separate primary or outside work sheets past the printing line on said platen, a plurality of stop means carried by said cross bar, and a key controlled stop carried by said auxiliary carriage and which coacts with said stop means to lock the auxiliary carriage to the platen carriage in different predetermined positions thereon. 60

57. The combination of a platen carriage, a cylindrical platen carried thereby and cooperative with the innermost of two work-sheets to 70

be collated, a supporting rail or cross bar that is carried by said carriage and extends substantially throughout the length of the platen carriage and platen, an auxiliary carriage, roller bearings for supporting said auxiliary carriage above the platen for free movement along said supporting rail or cross bar, hand controlled means for arresting said auxiliary carriage in any one of a plurality of positions to which it may be moved 10 along said supporting rail, and means carried by

said auxiliary carriage for carrying and feeding separate outside work sheets to be collated with reference to the said inside sheets whereby a separate outside work sheet thus carried by the auxiliary carriage may be rapidly moved therewith 5 along the platen for correlating it relatively to an inside work sheet on the platen and whereby said outside work sheet also may be fed in a line space direction on said auxiliary carriage.

FREDERICK A. HART. 10

CERTIFICATE OF CORRECTION.

Patent No. 2,075,578.

March 30, 1937.

FREDERICK A. HART.

It is hereby certified that error appears in the printed specification of the above numbered patent requiring correction as follows: Page 7, first column, line 5, claim 4, for the word "operative" read inoperative; and that the said Letters Patent should be read with this correction therein that the same may conform to the record of the case in the Patent Office.

Signed and sealed this 16th day of November, A. D. 1937.

Henry Van Arsdale,
Acting Commissioner of Patents.

be collated, a supporting rail or cross bar that is carried by said carriage and extends substantially throughout the length of the platen carriage and platen, an auxiliary carriage, roller bearings for supporting said auxiliary carriage above the platen for free movement along said supporting rail or cross bar, hand controlled means for arresting said auxiliary carriage in any one of a plurality of positions to which it may be moved 10 along said supporting rail, and means carried by

said auxiliary carriage for carrying and feeding separate outside work sheets to be collated with reference to the said inside sheets whereby a separate outside work sheet thus carried by the auxiliary carriage may be rapidly moved therewith 5 along the platen for correlating it relatively to an inside work sheet on the platen and whereby said outside work sheet also may be fed in a line space direction on said auxiliary carriage.
